DISPENSER FOR ROLLED PAPER WITH
AUTOMATIC HOLDING BRAKEStephen E. Weakland and Lynn L. Simpson,
Portland, Oreg.

Application May 25, 1949, Serial No. 95,319

1 Claim. (Cl. 242—55.5)

1

This invention relates generally to paper holding and dispensing devices for paper in web form and particularly to a dispenser for rolled paper with automatic holding brake.

The main object of this invention is to provide a dispenser of the class described in which rolled paper may be conveniently inserted and withdrawn with a minimum amount of effort.

The second object is to construct a holder which will automatically hold the paper while being torn and completely release it while being withdrawn.

The third object is to so construct the dispenser that the roll of paper cannot be misplaced therein and that there is only one way in which the paper can be threaded when starting a new roll.

The fourth object is to reduce the amount of waste by spinning a roll during unsuccessful attempts to draw paper therefrom.

The fifth object is to construct a dispenser which will operate with equal success with various widths and grades and thicknesses of paper.

We accomplish these and other objects in the manner set forth in the following specifications as illustrated in the accompanying drawing, in which:

Fig. 1 is a front elevation with the door open.

Fig. 2 is a section taken along the line 2—2 in Fig. 1 but showing the door closed and brake released.

Fig. 3 is a front elevation showing the door closed.

Fig. 4 is a partial section similar to Fig. 2 but showing the brake set.

Fig. 5 is a bottom view of the device.

Like numbers of reference refer to the same or similar parts throughout the several views.

Referring in detail to the drawing there is shown a back 10 having the fixed sides 11 which are held in proper relationship by the partial top 12 and the tie 13 which unites the lower edges 14 of the sides 11.

Journalling across the sides 11 is a paper roll shaft 15 provided with a wooden core 16, upon which is mounted a roll of paper 17.

The sides 11 are rounded on the upper front corners 18 which are tangent to the top 12 and also tangent to the vertical front portion 19 of the sides 11.

Below the portions 19 are the concave edges 20 which, together with the edges 18 and 19, are provided with an inturned flange 21 against which rests a door 22 which is joined by the hinges 23 to the top 12.

The door 22 conforms closely to the shape of the sides 11 and at its lower end 23 extends tangentially from the curved portion 24 and terminates in a saw tooth tearing edge 25 at each

2

end of which is a sharp point 26 which engages the paper 27 and pierces it, thereby starting the tear.

In addition to the foregoing, we have provided an automatic brake consisting of a shaft 28 which is supported by the sides 11, on which shaft is pivotally mounted a plate 29 whose rear edge 30 is upwardly curled toward the back 10.

The forward edge of the plate 29 is down-turned to form a shoe 31, over which paper 32 from the roll 17 rides when pulled downwardly as shown in Fig. 2. This downward pull unbalances the plate 29 causing the brake shoe 21 to move away from the inner face of the front edge 22. Suitable latches (not shown) are provided for the door 22 to enable it to resist the tearing action without being opened.

It can be seen from the foregoing that we have provided a dispenser which, although simple and inexpensive, will effectively dispense any kind of paper in roll form.

Obviously any size of dispenser desired can be made. Our invention is directed particularly to the automatic brake mechanism and the related elements of the dispenser.

We claim:

A dispenser for toilet tissue in roll form, comprising a casing including a pair of end walls together with a back and partial top uniting said end walls, a tie between the lower front ends of said side walls, a floor plate pivotally mounted in said side walls having an upturned rear edge tangent to said back and having its front edge down-turned to form a shoe in front of said tie, a door hinged to the forward edge of said partial top and extending in an inclined manner past the down-turned shoe, said extending portion having a serrated edge with projecting teeth at each end, said floor plate having its rear portion heavier than its front portion whereby the shoe will normally hold the paper against the back of the inclined part of said door and to be released when the paper is withdrawn.

STEPHEN E. WEAKLAND.
